UNITED STATES PATENT OFFICE

172,251

SHOE

Vincent Salmeri, Ville La Salle, Quebec, Canada

Application November 7, 1952, Serial No. 22,176

Term of patent 14 years

(Cl. D7—7)

To all whom it may concern:

Be it known that I, Vincent Salmeri, a citizen of Canada, residing at Ville La Salle, Province of Quebec, Canada, have invented a new, original, and ornamental Design for a Shoe of which the following is a specification, reference being had to the accompanying drawing, forming part thereof.

Figure 1 is a top plan view of the shoe embodying my new design.

Figure 2 is a side elevation of the shoe; and

Figure 3 is a front elevation thereof.

I claim:

The ornamental design for a shoe, as shown.
